PERSONALIZED FLOOR MAT

Rankin M. Daugette, Jacksonville, Ala.

Application May 21, 1953, Serial No. 25,149

Term of patent 14 years

(Cl. D9—6)

To all whom it may concern:

Be it known that I, Rankin M. Daugette, a citizen of the United States of America, residing at Jacksonville, in the county of Calhoun and State of Alabama, have invented a new, original, and ornamental Design for a Personalized Floor Mat, of which the following is a specification, reference being had to the accompanying drawing, forming a part thereof, wherein:

Fig. 1 is a top plan view of a personalized floor mat, showing my new design;

Fig. 2 is a longitudinal edge view thereof;

Fig. 3 is a detail sectional view on an enlarged scale taken on the line 3—3 of Fig. 1; and

Fig. 4 is a detail sectional view on an enlarged scale taken on the line 4—4 of Fig. 1.

The dominant features of my floor mat design reside in those portions shown in full line.

What I claim is:

The ornamental design for a personalized floor mat, as shown and described.
